CANISTER OR SIMILAR ARTICLE

Charles O. Bliss, Los Angeles, Calif.

Application July 10, 1956, Serial No. 42,192

Term of patent 14 years

(Cl. D44—6)

FIG. 1

FIG. 3

FIG. 2

Fig. 1 is a top plan view of a canister, showing my new design;

Fig. 2 is a side view thereof;

Fig. 3 is a bottom plan view thereof; and

Fig. 4 is a fragmentary vertical sectional view, on a larger scale.

I claim:

The ornamental design for a canister or similar article, substantially as shown.
